UNITED STATES PATENT OFFICE.

CARL A. DIEDERICH, OF PITTSBURGH, PENNSYLVANIA.

MECHANICAL TOY.

Application filed October 28, 1925. Serial No. 65,326.

This invention relates to a mechanical toy and important objects thereof are to provide a mechanical toy which is characteristic of a horse running race and which embodies interchangeable figurative horses mounted for operative movement imitable of running horses.

Further objects of the invention are to provide a toy of the type stated, in a manner as hereinafter set forth, which is simple in its construction and arrangement, strong, durable and efficient in its use, entertaining, compact, attractive in appearance and comparatively inexpensive to manufacture.

With the foregoing and other objects in view, which will appear as the description proceeds, the invention, resides in the combination and arrangement of parts and in the details of construction hereinafter described and claimed, it being understood that changes in the precise embodiment of the invention herein disclosed can be made within the scope of what is claimed without departing from the spirit of the invention.

In the drawing forming a portion of this specification and wherein like numerals of reference designate corresponding parts throughout the several views:—

Figure 1 is a top plan view of a mechanical toy in accordance with this invention, with a portion of the cover plate broken away.

Figure 2 is a side elevation of the device with a side wall removed therefrom and partly in section.

Referring in detail to the drawing 1 denotes a body portion consisting of a bottom 2, the end walls 3 and the side walls 4 connected together to provide a rectangular casing. The body portion 1 is provided with a cover plate 5 which is secured to the former by means of the screws 6, or in any other suitable manner.

The top face of the cover plate 5 constitutes a straightaway race track, and the simulation of the latter is augmented by the provision of an ornamental, vertically disposed fence structure 7, which extends along the marginal edges of the top face of the cover plate 5.

The cover plate 5 is formed with a plurality of elongated slots 8 which extend longitudinally relatively to the cover plate 5. The slots 8 are arranged into three rows each of which consists of a series of three slots 8. The slots 8 of each of the rows are trans-

versely aligned and extend parallel relatively to each other, and the slots 8 of one row are longitudinally aligned with respect to the corresponding slots of the other rows. 60

A rectangularly shaped, transversely disposed carrier 9 is associated with each row of slots 8. Each of the carriers 9 is provided at its rear end with a pair of projections 9' which are pivotally mounted in vertically disposed grooves 10, formed in the side walls 4 of the casing 1. Three transversely aligned supports 11 are fixed to the top of each of the carriers 9, adjacent to the forward ends of the latter. The upper end 70 of each of the supports 11 extends into a respective slot 8 and is provided with a longitudinally extending groove 12 formed on its top face, a figure 13, representative of a running horse with jockey, is detachably 75 secured to the top of each of the supports 11 by having its lower end forced into the groove 12.

Each of the carriers 9 is associated with an actuating bar 14 extending transversely 80 in the body portion 1 and disposed beneath and in engagement with the forward portion of respective carriers 9. Each of the actuating bars 14 is provided with a pair of trunnions 15 which are journaled for rotation in respective side walls 4, of the body portion 1.

A double groove pulley 16 is fixed on one trunnion 15, of the intermediate disposed actuating bar. This trunnion is also provided with a squared extension 17, which extends through the associated side wall and is adapted for the reception of a crank (not shown) or other mechanical medium for operating the device. A single groove pulley 95 18 is fixed to a trunnion 15 of the rearwardly and forwardly disposed actuating bars 14.

Belts 19 connect the double groove pulley 16 with the intermediate actuating bar, with the pulleys 18 of respective rearwardly and forwardly disposed actuating bars. The operation of the double groove pulley 16 will simultaneously impart a rotary movement to the other pulleys 18 and to the 105 actuating bars associated with the latter.

Each of the actuating bars 14 is substantially rectangularly shaped in transverse cross section and is considerably greater in width than thickness. Owing to this variation in width of the bars 14 with respect to their thickness, the rotation of the bars 14

2
will alternately elevate and lower the pivotally connected carriers 9, thereby imparting a bobbing movement, typical to running horses, to the figures 13.

5 It will be noted that the figures 13 may be readily detached from their supports 11, whereby the device may be reduced to a more compact form to facilitate transportation and storage.

10 What I claim is:

In combination, a toy comprising a rectangular casing, a cover plate representing a race track secured to the top of said casing, said cover plate formed with a plurality of elongated slots, carriers having their rear ends pivotally connected in said casing, supports fixedly mounted on said carriers and having their upper ends ex-

tending into said slots, the top of each of said supports formed with a groove, a figurative object carried by each of said supports and detachably connected in said grooves, actuating bars rotatably mounted in said casing and engaging the forward end of said carriers, said actuating bars being 25 rectangularly shaped in transverse cross section and of a greater width than thickness for alternately elevating and lowering the said carriers during the rotation thereof, and means associated with said actuating bars to cause the simultaneous operation thereof, substantially as described and for the purpose set forth.

In testimony whereof I affix my signature.

CARL A. DIEDERICHHS.
